[57] CLAIM

The ornamental design for a side portion of a shoe upper, as shown and described.

DESCRIPTION

FIG. 1 is a perspective view of a side portion of a shoe upper showing our new design;

FIG. 2 is a side elevational view thereof;

FIG. 3 is a front elevational view thereof;

FIG. 4 is a rear elevational view thereof; and,

FIG. 5 is top plan view thereof.

The broken line showing of a shoe outsole and the remaining portion of the upper in FIGS. 1-5 is for illustrative purposes only and forms no part of the claimed design.
